UNITED STATES PATENT OFFICE.

ERNEST WILLIAM LEE, OF TORONTO, ONTARIO, CANADA.

FLOUR-SIFTER.

1,007,119.

Specification of Letters Patent. Patented Oct. 31, 1911.

Application filed March 21, 1911. Serial No. 615,833.

To all whom it may concern.

Be it known that I, ERNEST WILLIAM LEE, of the city of Toronto, in the county of York, in the Province of Ontario, Canada, have invented certain new and useful Improvements in Flour-Sifters, of which the following is the specification.

My invention relates to improvements in flour sifters, and the object of the invention is to devise a machine of this class in which the flour will be blended prior to the sifting operation of the machine, and this too without the necessity of constant attention of the man who feeds the machine.

A further object is to provide means to feed the flour uniformly without liability of clogging.

Another object is to provide an equal distribution on the sieve and insure against the liability of clogging on the sieve.

A still further object is to separate foreign matter from the pure flour and automatically discharge it from the sifter.

A still further object is to provide a simple means for discharging both the flour and the foreign matter separately.

An object also is to so construct the machine that no dust will escape.

To effect these objects I have constructed my sifter of a hopper having the central adjustable division tube leading from the bottom of the hopper provided with a screw conveyer, the tube being cut away in taper like form at the discharge end, a rotary sifter surrounding the discharge end of the tubular conveyer supported on suitable rollers and suitably driven, and preferably cone-frustum-shape in form and provided with an annular end for the collection of foreign matter, said end having orifices through which the foreign matter is discharged into a collecting bin, and a suitable silting chamber in which the sifter is located having an orifice at the bottom, and a screw conveyer leading thereto, the said orifice communicating with an elevator of the usual bucket type, and the parts being otherwise constructed and arranged as hereinafter more particularly explained.

Figure 1, is a sectional perspective view showing portions broken away to exhibit the construction of my invention. Fig. 2, is a sectional plan. Fig. 3, is a vertical section on the line *x-y* Fig. 2. Fig. 4, is a detail of the divided blending hopper.

In the drawings like letters of reference

indicate corresponding parts in each figure.

A is the floor of the building under which my machine is placed.

B is the main casing of the machine, which is suitably secured underneath the floor and is provided with a rounded bottom.

C is a tubular conduit, which extends through one end of the main casing and D is a shaft, which extends from end to end of the machine, and is journaled in suitable bearings E and E'. The portion of the shaft extending through the conduit C is preferably provided with a convolute spiral forming a screw conveyer C', and the tubular conveyer at the inner end is cut away at C² from the top inwardly being gradually beveled toward the center of the shaft for a purpose which will hereinafter appear.

F is the hopper in which the flour is placed and blended. The hopper projects above the floor for the most part and extends down in tapered form to an orifice F' immediately above the conveyer C.

F² is a partition, which is adjustable by means of the screw spindles F³ and F⁴, which extend through nuts F⁵ and F⁶ attached to the partition. The spindles F³ and F⁴ run freely through suitable bearings 2 and 3 at the outside of the walls of the hopper and are connected together by sprocket chains and wheels G G' and G², so that the partition may be adjusted by the handle G³ in order that the flour may be blended either equally or in unequal proportions.

H is a rotary sieve, which is located in the casing B and is cone-frustum shape being provided at the larger end with an inwardly extending annular lip H', which terminates in a rim H² from which extends a collecting ring B³ having discharge openings B⁴ and an exterior bearing ring B². The bearing rings ride on rollers B⁶ journaled on pins B⁷. The opposite end of the sieve H is provided with a circular end plate H²¹ and the sieve is reinforced by the longitudinal exterior rods I extending through the end plate H²¹ and the ring B², the ends of the rods being threaded and suitably held in the plate and ring by nuts. The plate H²¹ is secured to the shaft D so that the sieve H rotates in unison with the shaft.

J is a drum secured to the shaft and provided with an end plate J'. The drum and the plates H²¹ form a ring bearing for the sieve at the small end, the other end of the

sieve being supported upon the rollers B^6 hereinbefore referred to. The shaft D is rotated by means of a sprocket chain K and sprocket wheel K'.

5 L is a receptacle located at the large end of the sieve underneath the end plate. Within the receptacle L is placed a box L' having an open top. This box receives the foreign matter deposited from the sieve.

10 M is an opening at the bottom of the casing B.

N is a shaft journaled in suitable bearings and provided with screw conveyers N' and N² both feeding to a point intermediate of the length of the shaft.

15 O is a bucket chain conveyer, which passes around the shaft N, the lower wheel being secured on the shaft. The bucket chain conveyer is provided with a suitable casing O'.

20 and the purified flour is fed upwardly to a suitable place of deposit through the casing O'.

The shaft N is provided with a sprocket wheel N³ at one end, which is connected by 25 a sprocket chain N⁴ to a sprocket wheel N⁵ on the shaft D.

30 The tubular conveyer C and the tubular conveyer N are all practically the same size, so that the feed and the discharge are identical.

35 The flour is fed in through the hopper where it passes into the screw conveyer blended, and by such conveyer is carried downwardly to the sieve where the flour passes over the beveled end of the tube, so that it is gradually distributed evenly throughout the length of the sieve. The sieve in rotating effectually screens the flour and the flour proper passes down through

the opening M whence it is conveyed by the 40 bucket conveyer O to a suitable place of deposit. The foreign matter works down to the lower part of the sieve over the lip H' into the annular collecting ring B³ from which it is discharged into the receptacle 41 L from which it may be removed when desired.

I should mention that I preferably provide a baffle plate 4 affixed to the tubular conveyer C near the large end of the sieve. 50 This plate is circular and extends comparatively close to the wall of the sieve. By the provisions of such a plate I am enabled to deflect the flour dust back, so that it will not pass into the annular ring B³ but will 55 be deflected and pass through the sieve with the flour and be carried away by the flour conveyer.

Although I have shown and described in detail the parts involved in my invention it 60 will, of course, be understood that various changes may be made without departing from the spirit of the invention yet coming within the scope of the claim.

What I claim as my invention is: 65

In a flour sifter, a cone-frustum shaped sieve having a slightly gradually contracted portion at its large end forming an inturned annular lip, and an annular collecting ring 70 secured to the sieve to the outside of the lip and having discharge holes therein and closures for the ends of the sieve, as and for the purpose specified.

ERNEST WILLIAM LEE.
